UNITED STATES PATENT OFFICE.

ISAAC SHERCK AND JOSEPH BATIG, JR., OF FREMONT, OHIO.

APPARATUS FOR WAXING PAPER, &c.

SPECIFICATION forming part of Letters Patent No. 345,864, dated July 20, 1886.

Application filed April 15, 1886. Serial No. 192,888. (No model.)

To all whom it may concern:

Be it known that we, ISAAC SHERCK and JOSEPH BATIG, Jr., of Fremont, in the county of Sandusky and State of Ohio, have invented

5 certain new and useful Improvements in Apparatus for Waxing Paper, &c.; and we do hereby declare the following to be a full, clear, and exact description of the invention, such as will enable others skilled in the art to which 10 it appertains to make and use the same.

Our invention relates to an improvement in apparatus for waxing paper or other material.

The object is to provide means for coating to a greater or lesser thickness, or partially 15 or completely saturating paper or other material, with wax, paraffine, and the like, by the capillary process, and to further provide a simple, effective, and economical apparatus for the above purpose.

20 With these ends in view our invention consists in certain features of construction and combinations of parts, as will be hereinafter described and pointed out in the claims.

The accompanying drawing represents the 25 apparatus in vertical longitudinal section.

A represents a tank in which the wax, paraffine, &c., is kept in a liquid state by heat from a series of steam-radiator pipes, B, or by any other suitable means. From the tank A 30 a pipe, a, leads to a well, C, situated as low or lower than the tank A, in order to cause the melted wax to flow freely from the tank thereto. The pipe a is provided with a stop-cock, a', to regulate the flow of the melted wax.

35 Over the well C is a porous slab or series of slabs, D, of stone, wood, or other suitable material, kept at the desired temperature by a series of radiator-pipes, b, which may conveniently be a continuation of the pipes B, or may

40 be a separate series. Through a slot in the slab D, or through an opening between two of the slabs D, a bunch of wicking, felt, or other fibrous or porous material, E, adapted to raise the wax by capillary attraction, is located and 45 preferably surrounded by a tube, e. The latter is adapted to be raised and lowered by a pinion, f, on a rotary shaft, F, which meshes with a series of teeth or notches, f', on the tube. At a short distance from the tube e

50 there is a second opening in the slab D, or between the slabs, through which a second bunch or block of wicking, felt, or the like, E', pro-

jects. The lower end of the wicking E' does not, however, extend to the surface of the melted wax in the well, and is employed as a 55 return-conduit, as will hereinafter appear.

G represents the paper. It is drawn from a reel, H, over a pair of rollers, I, and beneath a pressure-roller, i. The rollers I are synchronously geared, and the roller i is driven 60 by its frictional contact with the roller I, and the tension of the paper is regulated thereby. From the rollers I i the paper extends up and over the face or faces of the slab or slabs D, over the top of the wicking E, and thence 65 along the face or faces of the slab or slabs D, over the top of the wicking E'; thence to the set of rollers K k, similar to and geared in the same manner as the rollers I i; thence into the receptacle L, and thence through a set of 70 rollers, M m, to the cutter N.

The cutter or cutters N consist, essentially, of a drop-knife or rotary cutter or cutters operated by a wheel, O, geared with the rollers M m, which, by a series of cams or other equivalent means, alternately engage and release 75 a lever, P, attached to the drop-knife.

The paper as it passes over the slabs is kept heated by heat from the slabs, and is hottest on the side which is to receive the wax. As 80 it passes over the top of the wicking E it is covered with wax drawn up from the well C by the wicking, felt, &c. As it passes along over the slabs after leaving the wicking E any superfluous wax is removed by the second set 85 of wicking, E', the wax being returned through said wicking into the well.

The pressure of the wicking in the tube e is regulated by raising or lowering the tube, and the waxed surface may be operated upon by 90 two or more bunches of wicks or felt, E', instead of one. The same arrangement might also be employed above the paper for coating the upper side as well as the lower.

We are aware that it is not new to pass the 95 paper on a felt block the lower end of which is immersed in a tank containing the wax. We are also aware that it is old to provide a paper-waxing machine with one or more wick-supports and one or more guides, the parts 100 being arranged so that the paper rubs over the side of the wick, and hence we make no claim to such construction.

It is evident that slight changes might be

resorted to in the form and arrangement of the several parts described without departing from the spirit and scope of our invention; hence we do not wish to limit ourselves strictly to 5 the construction herein set forth; but,

Having fully described our invention, what we claim as new, and desire to secure by Letters Patent, is—

1. In apparatus for waxing paper, the combination, with a porous slab or slabs over which the paper is drawn, of a bunch of capillary tubes leading from a reservoir beneath the said porous slab or slabs up through the same into contact with the paper, substantially as set 15 forth.

2. In apparatus for waxing paper, the combination, with a porous slab or slabs and means for keeping them at the desired temperature, of a vertically-adjustable bunch of capillary tubes leading from a well beneath the slab or slabs to a point above their upper surface, substantially as set forth.

3. In apparatus for waxing paper, the combination, with a porous slab or slabs and 25 means for heating the same, of a bunch of felt or other suitable material adapted to feed the wax up through an opening in the slab, or between the slabs, and a bunch of capillary tubes adapted to convey the superfluous wax down 30 through an opening in the slab or slabs, substantially as set forth.

4. In apparatus for waxing paper, the combination, with one or more slabs of porous ma-

terial—such as soapstone, pumice stone, and the like—and means for passing paper over 35 their surface, of a bunch of capillary tubes enclosed within a casing, and a pinion and series of notches for adjusting the casing, and hence the capillary tubes, substantially as set forth.

5. The combination, with the tank of melted 40 wax, the well located as low or lower than the tank, and a pipe leading from the tank to the well and provided with a stop-cock, of the porous slab or slabs located over the well, the bunch of capillary tubes leading from the well 45 through the slab or slabs, and the several sets of rollers adapted to regulate the movement of the paper over the slab or slabs, substantially as set forth.

6. In an apparatus for waxing paper, the 50 combination, with a porous slab or slabs over which the paper is drawn, and a bunch of capillary tubes leading from the reservoir beneath the said porous slabs up through the same into contact with the paper, and rollers 55 for feeding the paper, of the cutter or cutters located and operated substantially as set forth.

In testimony whereof we have signed this specification in the presence of two subscribing 60 witnesses.

ISAAC SHERCK.
JOSEPH BATIG, JR.
